FURNACE-RETORT.

1,418,838.

Specification of Letters Patent. Patented Apr. 25, 1922.

Application filed May 31, 1919. Serial No. 300,937.

To all whom it may concern:

Be it known that we, WILLIAM BARTON EDDISON and HARRY S. OWENS, citizens of the United States, and residents, respectively, of Irvington, county of Westchester, and State of New York, and of Irvington, county of Essex, and State of New Jersey, have made certain new and useful Improvements in Furnace-Retorts, of which the following is a specification.

The invention relates to improvements in furnace-retorts and is particularly directed to a construction having a longitudinally extending tubular inner wall or retort shell within which coal is heated in order to carbonize or partially carbonize it and about which tubular inner wall or retort shell there is masonry constructed so as to provide one or more longitudinally extending combustion chambers from which the products of combustion flow through narrow or restricted openings or passageways to the places where the products of combustion can be employed for heating the tubular inner wall or retort shell.

The masonry is preferably constructed so that there are a number of vertically and transversely extending partitions, serving to define corresponding vertically and transversely extending spaces or heating flues constituting the places where the products of combustion can be employed for heating the tubular inner wall or retort shell. The spaces are arranged in a set or sets, which set or sets preferably extend along the tubular inner wall or retort shell to receive the products of combustion after passing through the restricted openings or passageways leading from the combustion chamber or combustion chambers.

The invention is directed to the features above referred to and also to others hereinafter fully set forth and described.

As illustrating a specific manner in which the invention may be realized reference is made to the accompanying drawings forming a part of this specification, in which drawings—

Figure 1 is a vertical transverse sectional view of the combined furnace and retort. This figure is a view taken as on the plane indicated by the line 1—1 of Figure 2 looking in the direction of the arrows.

Figure 2 is a vertical longitudinal sec-

tional view of the furnace-retort shown in Figure 1 and is a view taken as on the planes indicated by the broken line 2—2 of Figure 1 looking in the direction of the arrows.

Referring now to the drawings in detail, the furnace-retort is designated by 1 and is referred to as such since it combines the retort proper, as 2, and the furnace proper, as 3, whereby the retort is exteriorly heated. The retort has a longitudinally extending tubular inner wall or retort shell heart-shaped in cross-section and designated 2a. At one end of the retort there is located a head 4 and means, indicated as 5, for feeding coal to the upper interior portion of the retort and this end of the retort is referred to as the charging end. The other end of the retort has a head, as 6, and is referred to as the discharging end. A pair of shafts, as 7, 7, extends through these heads and each carries paddles or blades, as 8, constructed so as to agitate or mix the material within the retort and so as to convey the material from the charging end of the retort toward the discharging end thereof. The coal which is charged into the retort at one end thereof is progressively and uniformly heated throughout in a manner to partially distill or partially carbonize it and the partially distilled residue passes from the retort through a discharge opening or conduit 9 having a suitable valve or sealing means 10 at the lower portion thereof for permitting a discharge of the material. The exterior of the tubular inner wall or retort shell is heated, as will hereafter more fully appear, and the gases and vapors given off during the heating operation are withdrawn, as through piping 11.

The construction of the feeding means is such that the coal can be charged to the interior of the retort without permitting the entrance of air to or the escape of gases from the interior of the retort. The construction, where the shafts pass through the heads, is also such as to permit the shafts to rotate without permitting the entrance of air into or the escape of gas from the interior of the retort and the valve or sealing means 10 is also such as to permit the material to be discharged from the retort when properly carbonized without permitting the entrance of any substantial amount

of air to the retort. In other words, the retort may be considered as substantially air-tight and constructed so that the carbonizing can be carried out as a continuous operation.

As to the construction which provides the furnace proper 3 of the retort, it will be observed that this is masonry and provides a base or floor construction, as 12, extending 10 horizontally, and both longitudinally and transversely, and that it also provides two upright side walls 13 extending upwardly from the base or floor construction 12 and also extending longitudinally from what 15 may be referred to as the upright transversely extending end walls 14 and 15. In the base or floor construction 12 there is provided a fire-brick 16 built so as to form two longitudinally extending combustion 20 chambers 17 and 18 separated by longitudinally extending upright partitions 19. The partition 19 and side walls 20 may be referred to as the side walls of the combustion chamber and at intervals along the combustion 25 chamber there are located transversely extending arches 21 constituting a series of arches extending from combustion chamber side wall or side portion 20 to combustion chamber side wall or longitudinally extending 30 upright partition 19. The portion of each side wall which defines the combustion space has an upper part extending upwardly and inwardly whereby at the uppermost portion of the combustion spaces there is left 35 a series of relatively narrow slits or restricted openings as 22. The width of each of the openings is clearly shown in Figure 1 and the length of the openings is clearly shown in Figure 2. At one end of each of 40 the combustion chambers there is located a burner 23 constructed so that there is provided a mixture of gas and air in a manner whereby combustion can take place along substantially the full length of the combustion chamber. In other words, a mixture 45 of gas and air is projected in a longitudinal direction through the medium of this burner into and along each combustion chamber. The burner 23 has a valve-controlled means 50 23^a for supplying fuel to the combustion chamber and also a damper-controlled opening 23^b controlled by a damper 23^c through which air for supporting combustion enters the chamber.

55 The upper portion of the side walls 13 is constructed so as to provide longitudinally extending waste heat flues 26. A horizontal roof 25 extends transversely from one main side wall to the other and also longitudinally 60 from one end wall to the other.

There is also shown in the drawings a series of vertically and transversely extending partitions 27 located over and in register with the arched portion 21 and these partitions 27 extend from the base or floor con-

struction 12, main side walls 13 and roof 25 on the one hand to or substantially to the tubular inner wall or retort shell on the other. In order to permit of expansion of the tubular inner wall or retort shell with 70 respect to each of the transversely extending partitions the construction which provides them is cut off or made so as to leave an expansion space, as 28. The products of combustion pass upwardly through each of 75 the combustion chambers, as 17 or 18, through the series of restricted openings or passageways 22 into the lower portion of the several vertically extending spaces or heating flues 29 on opposite sides of the 80 transverse partitions.

In order to protect the lower portion of the tubular inner wall or shell from the intense heat of the upwardly flowing hot products of combustion as they pass through 85 the restricted passageways into the several heating flues baffle plates 30 are provided, of carborundum for example, which are arranged between the restricted openings 22 and the portion of the tubular inner wall 90 or retort shell opposite thereto. As previously indicated, the vertically and transversely extending spaces are divided into two sets, one set at or along the longitudinal right hand side of the retort shown in 95 Figure 1 and the other set at or along the longitudinal left hand side of the retort shown in the same figure, this division being effected by means of the vertically and longitudinally extending partition 31 which extends from the floor construction to the under side of the tubular inner wall or retort shell. The products of combustion pass from each of the heating flues 29 through 100 openings 32 controlled by a damper 33 into 105 the waste heat flue 26, previously referred to, and which openings are relied upon to conduct the waste gases from the furnace.

The tubular inner wall or retort shell may be made of metal or of suitable refractory 110 material, as carborundum block, and the transversely extending partitions are preferably made of suitable refractory material as, for example, specially constructed brick of the shape indicated in the drawings.

While according to the specific illustration of the invention and according to the preferred form thereof there is employed a construction providing two longitudinally extending combustion chambers located in 120 the base or floor construction 12, still according to the broader aspect of the invention it would be possible to make a construction wherein there is only a single longitudinally extending combustion chamber 125 from which the products of combustion flow laterally, vertically or otherwise, through a restricted opening or passageway or passageways to the places where the tubular inner wall or retort shell is heated. It will 130

also be manifest that the invention may be embodied in various other forms and modifications without departing from the spirit and scope thereof.

5. What we claim is:

1. A furnace-retort comprising in combination a longitudinally extending retort shell providing the retort proper of the furnace-retort, mixing and conveying means therein, masonry on the exterior of the retort shell and with the retort shell providing the furnace proper of the furnace-retort, the masonry being constructed so as to have a longitudinally extending combustion space below the retort shell, and means for supplying gas and air to the interior of said combustion space and at an end thereof, the furnace-retort construction being such that vertically extending heating flues are arranged along the retort shell and also being such that products of combustion pass from the combustion space into each of the heating flues through a restricted passageway or opening leading from the combustion space to the heating flue.
2. A furnace-retort comprising in combination a longitudinally extending retort shell providing the retort proper of the furnace-retort, mixing and conveying means comprising overlapping paddles, and masonry on the exterior of the retort shell and providing with the retort shell the furnace proper of the furnace-retort, the masonry being constructed so as to provide longitudinally extending combustion spaces, one below the longitudinal right hand half of the retort shell and one below the longitudinal left hand half, the furnace-retort having means for supplying gas and air to the interior of each said longitudinally extending combustion space and at an end thereof, the furnace-retort construction being such that vertically extending heating flues are arranged along the retort shell and also being such that products of combustion pass into each of the heating flues through a restricted passageway or opening leading from the combustion space corresponding to the heating flue.
3. A furnace-retort having a longitudinally extending retort shell, mixing and conveying means therein, refractory masonry on the exterior of said shell constructed so as to provide a floor portion below the retort shell and so as to provide upwardly extending side walls along the exterior of the retort shell, the floor portion having hollow longitudinally extending members forming or providing combustion spaces, and means for supplying gas and air to the interior of each of the combustion spaces, the furnace-retort having vertical transverse partitions dividing the space between the floor construction and side walls on the one hand and the retort shell on the other into heating flues arranged along the retort shell, the masonry floor being constructed so that the products of combustion pass from said combustion spaces through restricted openings into said heating flues, the masonry also having at and along the upper portions thereof longitudinally extending waste heat flues or passageways leading from the heating flues to the waste heat flues, and dampers for controlling the size of said openings.
4. A furnace-retort having a longitudinally extending retort shell, overlapping paddles for conveying material through said retort, and refractory masonry on the exterior of said shell constructed so as to provide a floor portion below the retort shell so as to provide side walls extending along the exterior of the retort shell and so as to provide a waste heat flue construction, the floor portion having therein a longitudinally extending combustion chamber, said furnace-retort having means for supplying gas and air to the interior of the combustion chamber, the furnace-retort also having transverse partitions dividing the space between the floor construction and side walls on the one hand and the retort shell on the other into a series of heating flues, the floor portion being constructed so that the products of combustion pass from the combustion chamber through restricted openings into said heating flues, the furnace-retort also having dampers for controlling the size of the openings or passageways through which the products of combustion pass from the heating flues into the waste heat flue construction.
5. A furnace-retort having a longitudinally extending retort shell, mixing and conveying means therein, masonry providing a floor portion below and spaced from the shell, a vertical and longitudinally extending partition extending from the floor portion to the exterior longitudinal central portion of the retort shell, vertically and transversely extending partitions arranged so as to define heating flues arranged along the exterior of the retort shell, the masonry floor being constructed so as to provide longitudinally extending combustion spaces therein, and means for supplying fuel and air to support combustion to the interior of said combustion spaces, which combustion spaces have at the upper portion thereof roof members with openings therein for providing restricted passageways through which products of combustion can pass from the combustion spaces to said heating flues, the masonry also providing at the upper portion of the furnace-retort longitudinally extending waste heat flues and having damper controlled openings through which the products of combustion can pass from said heating flues into the waste heat flues.
6. A furnace-retort having a longitudinally extending retort shell, mixing and conveying means therein, masonry providing a

floor portion below and spaced from the retort shell, vertically and transversely extending partitions arranged so as to define heating flues arranged along the exterior of the retort shell, the masonry floor being constructed so as to provide therein a longitudinally extending combustion chamber, means for supplying fuel and air to support combustion to the interior of said combustion chamber, which combustion chamber has at the upper portion thereof a roof with openings therein for providing restricted passageways through which products of combustion can pass from the combustion chamber to said heating flues, and baffle plates located on said roof openings and adjacent to said retort shell to protect the latter.

7. A furnace-retort having masonry providing a longitudinally extending combustion chamber and also having means for supplying fuel to and for permitting air for supporting combustion to enter the combustion chamber, the masonry being constructed so that restricted passageways are arranged or extend along the combustion chamber for permitting the products of combustion to flow laterally from the combustion chamber through said passageways to a place or places where the products of combustion heat the retort and mixing and conveying means in said retort.

8. A furnace-retort with masonry constructed so as to provide a longitudinally ex-

tending combustion chamber, the furnace 35 also having means whereby fuel and air are directed to one end of the combustion chamber in a longitudinal direction, the masonry being constructed so as to provide restricted lateral passageways extending along or ar- 40 ranged along said combustion chamber and also so as to provide laterally extending heating flues into which the products of combustion enter after passing from the combustion chamber through said passage- 45 ways and within which heating flues the products of combustion are located when heating the retort.

9. A furnace constructed so as to provide a longitudinally extending combustion 50 chamber so as to provide a series of longitudinally arranged restricted passageways for conducting the products of combustion laterally from the combustion chamber and also so as to provide a series of laterally or 55 transversely extending heating flues arranged to receive the products of combustion delivered thereto through said restricted passageways, the furnace also having means for supplying proportioned gas and 60 air that is projected in a longitudinal direction into the combustion chamber and mixing and conveying means therein.

This specification signed the 12th day of May A. D. 1919.

WILLIAM BARTON EDDISON,
HARRY S. OWENS.
